US0D1076560S

(12) **United States Design Patent** (10) Patent No.: **US D1,076,560 S**
(45) Date of Patent: ** May 27, 2025

(54) **ELECTRIC KETTLE**

- (71) Applicant: **WHIRLPOOL CORPORATION**, Benton Harbor, MI (US)
- (72) Inventors: **John W. McConnell**, St. Joseph, MI (US); **Ben C. Shao**, Clarendon Hills, IL (US); **Zhaoyi Yin**, Chicago, IL (US)
- (73) Assignee: **Whirlpool Corporation**, Benton Harbor, MI (US)
- (**) Term: **15 Years**
- (21) Appl. No.: **29/956,840**
- (22) Filed: **Aug. 9, 2024**

CLAIM

The ornamental design for an electric kettle as shown and described.

DESCRIPTION

FIG. 1 is a front perspective view of one embodiment of an electric kettle of the present design;
FIG. 2 is a rear perspective view thereof;
FIG. 3 is a first side elevational view thereof;
FIG. 4 is a second side elevational view thereof;
FIG. 5 is a front elevational view thereof;
FIG. 6 is a rear elevational view thereof;
FIG. 7 is a top plan view thereof; and,
FIG. 8 is a bottom plan view thereof.

(Continued)

The portions of the article shown in broken line form no part of the claimed design.

1 Claim, 8 Drawing Sheets
